[57] CLAIM

The ornamental design for a trigger for dispensing containers, as shown and described.

DESCRIPTION

FIG. 1 is a side view of a trigger for dispensing containers showing our new design, the opposite side being a mirror image;

FIG. 2 is an end view thereof;

FIG. 3 is a top view thereof;

FIG. 4 is an end view thereof, opposite that of FIG. 2; FIG. 5 is a bottom view thereof.

FIG. 1.

FIG. 2.

FIG. 3.

FIG. 4.

FIG. 5.
